UNITED STATES PATENT OFFICE.

LELAND L. SCOTT, OF SAVANNAH, MISSOURI.

TWO-CYCLE INTERNAL-COMBUSTION ENGINE.

Application filed July 31, 1922. Serial No. 578,669.

To all whom it may concern:

Be it known that I, LELAND L. SCOTT, a citizen of the United States, residing at Savannah, in the county of Andrew and State of Missouri, have invented a certain new and useful Improvement in Two-Cycle Internal-Combustion Engines, of which the following is a complete specification.

This invention relates to two-cycle internal combustion engines and has for one of its objects to produce a stationary inside head secured to one end of the cylinder and adapted to work in combination with an inverted cup-shaped piston, machined inside and outside.

Another object is to produce an engine of the general character mentioned equipped with a new and novel by-pass arrangement whereby a constant and steady suction shall be maintained on the up stroke of the piston, as well as a constant and steady compression of the mixture in the by-pass chamber on the down stroke of the piston, consequently entirely obviating a pause period pending the operation of the piston.

A further object is to provide a ported piston and by-pass structure of such character that the motor can be readily and easily adapted to function with an inlet valve of any suitable automatic or mechanical construction and in communication with the by-pass chamber of the engine.

Another object is to obviate the present sluggishness of the ordinary type of two-cycle engine, due to the fact that ordinarily the mixture is compressed in the crank case, or between the piston and a stationary head, and then at the proper time is allowed to escape through a more or less extended by-pass chamber into the cylinder. I have found that the sluggishness of an engine, constructed as just described, is due to a more or less condensation of the combustible mixture during its passage through the by-pass, and in order to overcome this difficulty I have designed the engine of this application, in which the combustible mixture is compressed in the by-pass chamber itself, and permitted to escape directly into the cylinder.

The objects of the invention are accomplished by providing the by-pass chamber with a long vertical port and forming the piston with a pair of similar spaced ports so arranged that one of the piston ports is constantly in register with the by-pass port

as will be explained in detail, hereinbelow.

With the objects named in view the invention consists in certain novel and useful features of construction and organization of parts as hereinafter described and claimed; and in order that it may be fully understood, reference is to be had to the accompanying drawings, in which:

Figure 1 is a central vertical transverse section taken through a two-cycle internal combustion engine embodying the invention.

Figure 2 is an enlarged face view of the by-pass chamber with its cap removed and with the piston in its withdrawn position.

In the said drawing, where like reference characters identify corresponding parts in all of the figures, 1 illustrates the cylinder block provided with the customary water circulating passages, 2 the cylinder head and 3 the crank-case which may be of any common and well-known type.

The cylinder block 1 is formed with an extension 4 projecting into the crank-case and forming a continuation of the cylinder, and secured to said extension is a fixed internal cylinder provided with the customary piston rings, and head 5, formed at its lower end with a flange 6 and secured in position to the lower end of the part 4 as clearly shown in Figure 1. The fixed cylinder head 5 is, of course, of cylindrical form and is formed at its lower end with a pair of oppositely disposed vertical slots 6 for the reception of a reciprocating part hereinafter mentioned.

Mounted in the cylinder for reciprocation therein is a piston 7 provided with suitable external piston rings and formed with an external skirt portion 8, said skirt portion being secured at its lower end to a wrist pin 9 secured to the connecting rod 10, as customary. At its upper end the piston head may be provided with a baffle plate 11 to direct the combustible mixture and aid in the scavenging of the engine as common in the art.

Formed in the side wall of the combustion chamber is an exhaust port 12 which is adapted to be uncovered by the piston when in its lowermost position, and preferably slightly below said portion is an intake port 13 although a suitable automatic valve inlet or an inlet valve driven mechanically from the crankshaft may be employed if desirable, said valve to open directly into the by-pass chamber, hereinafter referred to.

On the opposite side of the cylinder a large rectangular port 13^a is formed, which is in communication with a by-pass chamber 14 closed by a removable cap 15. In order to properly maintain the piston rings in position, a pair of vertically extending parallel cross bars 16 bridge the port 13^a, as will be readily understood.

The piston 7 is formed with an intake port 17 adapted to register at times with the port 13 for the purpose of drawing into the engine the combustible mixture, and on its opposite side, is formed with a pair of similar ports 18 and 19 so spaced vertically apart that one of these ports will be constantly in register with the long port 13^a in the cylinder wall regardless of the position of the piston.

The operation of the engine is substantially as follows:—Upon the upstroke of the piston, a vacuum will be created between the bottom of the piston and the fixed head 5 and immediately the port 17 registers with the intake port 13, the combustible mixture will be drawn into the engine. As one or the other of the ports 18 and 19 constantly register with the by-pass chamber, upon the commencement of the down stroke, this combustible mixture will be constantly and evenly compressed in the by-pass chamber 14 through the long vertical port 13^a.

Immediately the upper end of the long port 13^a is uncovered by the top of the piston, the combustible mixture will rush directly into the firing chamber as will be readily understood.

It will be apparent from the above that by means of the double port arrangement in the piston and the long port in the by-pass chamber, there is a continual and steady increase in the compression on the down stroke of the piston of the combustible mixture in the by-pass chamber, from which it is permitted to rush directly into the cylinder. I have found by experiment that when the combustible mixture is compressed between the underside of the piston and the fixed

head and then at the proper time permitted to rush around through a by-pass and into the cylinder, there is a resulting sluggishness of operation due to the fact that there is a condensation of the mixture pending its journey through the by-pass. With an engine embodying the invention, however, this draw-back is obviated.

From the above description it will be apparent that I have produced a device of the character described, which possesses all of the features of advantage set forth as desirable, and while I have described and claimed the preferred embodiment of the same, I reserve the right to make all changes properly falling within the spirit and scope of the appended claim.

I claim:—

In a two-cycle internal combustion engine, a cylinder having an elongated bore, an internal cylinder head bolted to the extremity of said cylinder and closing the end thereof and being provided with a series of piston rings, a piston for reciprocation in said cylinder and having its internal face in frictional contact with the rings of said internal head, a combustible mixture supply and an exhaust port in said cylinder, a by-pass chamber having a single port with its lower edge in horizontal alignment with the top of the internal head, a pair of ports in said piston; said by-pass and piston ports being so arranged that there shall be an uninterrupted compression of the combustible mixture in the by-pass chamber on the back stroke of the piston, one of said piston ports passing beyond the rings of the internal head.

In witness whereof I hereunto affix my signature.

LELAND L. SCOTT.
